US0D1106798S

(12) **United States Design Patent** (10) Patent No.: **US D1,106,798 S**
(45) Date of Patent: ** Dec. 23, 2025

(54) **COMBINATION LOCK**

(71) Applicant: **Shenzhen Hongshizi Technology Co., Ltd.**, Shenzhen (CN)

(72) Inventor: **Danfeng Shi**, Shanwei (CN)

(73) Assignee: **Shenzhen Hongshizi Technology Co., Ltd.**, Shenzhen (CN)

(**) Term: **15 Years**

(21) Appl. No.: **29/979,571**

(22) Filed: **Dec. 19, 2024**

(30) **Foreign Application Priority Data**

Nov. 25, 2024 (EM) 015083056-0001

(57) **CLAIM**

The ornamental design for a combination lock, as shown and described.

DESCRIPTION

FIG. 1 is a front perspective view of a combination lock, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view.

The broken lines in the drawings illustrate the portions of the combination lock, which form no part of the claimed design.

1 Claim, 7 Drawing Sheets
